UNITED STATES PATENT OFFICE.

MILTON A. FESLER, OF OAKLAND, CALIFORNIA, ASSIGNOR TO PETROLEUM HEAT AND POWER COMPANY, A CORPORATION OF DELAWARE.

BURNER.

1,415,434.

Specification of Letters Patent.

Patented May 9, 1922.

Application filed July 2, 1920. Serial No. 393,646.

To all whom it may concern:

Be it known that I, MILTON A. FESLER, a citizen of the United States, residing at Oakland, in the county of Alameda and State of California, have invented an Improvement in Burners, of which the following description, in connection with the accompanying drawings, is a specification, like characters on the drawings representing like parts.

10 The invention to be hereinafter described relates to burners employing oil as a fuel.

Burners of this type are supplied with the fuel oil in liquid form, and steam, compressed air or other atomizing agent is supplied to 15 the burner to break up or atomize the oil substantially into a gaseous state.

For efficient combustion of the oil it is desirable that the temperature thereof shall be raised preparatory to combustion to a predetermined point such, for example, as 160° F. The aim and purpose of the present invention, therefore, is to provide simple and efficient means automatically to maintain the oil at a temperature for efficient combustion 25 effect.

The character of the invention will be best understood by reference to the following description of one good form thereof shown in the accompanying drawings, wherein:

30 Fig. 1 is a transverse section through a burner equipped with the thermo-siphon means;

Fig. 2 is a view partly in section and partly in elevation of a portion of the construction 35 shown in Fig. 1;

Fig. 3 is a rear view of the burner support, the burner being removed therefrom; and

Fig. 4 is a horizontal section through the burner and support.

40 Referring to the drawings, the construction shown therein as one good form of the invention, comprises a burner support or housing 1, in the present instance, in the form of a substantially cylindrical casing 3 having 45 arms 5 and 7 projecting outward therefrom provided with holes 9 adapted to receive bolts for securing the support or housing in proper position on a wall of a furnace. The forward end of the cylinder 3 of the housing will

50 project into the furnace where it will be subjected to heat developed by combustion of the fuel delivered into the furnace by the burner. The present invention contemplates that this heat may be utilized to raise the temperature 55 of the oil to the desired point for efficient

combustion effect preliminarily to the delivery of the oil to the burner.

To this end the support or housing may be provided with a jacket 11 containing an oil passage 13 and a water passage 15 conveniently of annular form encircling the cylinder 3, the construction being such that said passages will be heated by the heat developed by the burner and conducted to said passages through the cylinder 3.

60 The oil for the burner may be taken from any suitable source of supply, and is usually forced to the burner by a pump of usual construction, and therefore, unnecessary to show herein. The oil may be conducted to the 70 passage 13 by a pipe which may be connected to a tapped hole 17 in the housing communicating with said passage 13. The oil will flow from said port around through said passage, and may be delivered therefrom 75 through a port 19 connected to means to be described for conducting the oil to the burner.

Suitable means may be provided to supply 80 water to the jacket passage 15. This means, in the present instance of the invention, comprises a stand pipe 21 having its lower end mounted on a support conveniently in the form of a base 23 adapted to rest on the floor. The upper end of the stand pipe may 85 be opened to the atmosphere. Projecting from the stand pipe is a branch pipe 25 leading to the burner and connected to a tapped hole 27 communicating with the water passage 15 of the jacket.

90 Communicating with the water passage is a port 29 leading to the interior of a casing 31 of general cylindrical form mounted on the support 1 and having its axis conveniently extending transversely to the axis of 95 the cylinder 3. This casing is provided with a tapped hole 33 adapted to be connected by a branch pipe 35 with the stand pipe 21 referred to, at a point at a substantial distance above the point of connection of the branch 100 pipe 25 therewith.

105 Mounted in the casing 31 is a valve 37 co-operating with a seat 39 formed in a wall dividing said casing into chambers 41 and 43.

Suitable means may be provided automatically to operate the valve 37 to regulate the flow of water through the water passage 15. This means, in the present instance, comprises a thermostat conveniently in the form of an expansible tube 45 having a head 110

47 connected by a stem 49 with the valve 37. The expansible tube 45 may have its end opposite the head 47 connected to a plug 51 threaded in the wall of the chamber 43. 5 This plug may have a kerf 53 therein and a screw 55 extending through portions of the plug at opposite sides of the kerf, and adapted to draw the same toward each other, in order to cause the thread of the plug to grip 10 the thread of the casing, and thereby hold the thermostat in different positions of adjustment therein. The adjustment of the thermostat will enable variation of the normal position of the valve 37 with respect to 15 its seat as required. The casing 31 may have the end containing the chamber 43 closed by a nut plug 57, and the end containing the chamber 41 may have a hole therein tapped to receive a plug 59. These plugs may be readily 20 removed to enable convenient access to the valve 37 in the thermostat. The latter may contain alcohol or other suitable liquid having the desired co-efficient of expansion.

The construction is such that if the temperature of the water rises, it will cause the thermostat 45 to expand and thereby move the valve 37 away from its seat. This will allow water to flow through the passage 15 and pass the valve 37 with cooling effect on 25 the jacket. On the other hand, if the temperature of the water falls, the thermostat tube will contract and move the valve 37 to its seat, thereby cutting off the supply of cooling water to the jacket. The stand pipe, 30 branch pipes and the water passages will tend to circulate water therethrough with the principle of the thermo-siphon. The water heated in the passage 15 will tend to rise and flow through the branch pipe 35 to the stand pipe, and the heat thereof may be dissipated through the open end of the stand pipe. The cold water will seek the lower end of the stand pipe and flow 40 through the branch pipe 25 up into the passage 15. The stand pipe may be supplied with water from time to time as required, in order to maintain the thermo-siphonic operation thereof.

In starting the burner, a Bunsen burner 50 61 of usual construction may be applied to the housing adjacent the water passage 15, and may be permanently connected to the housing if desired. The heat from the Bunsen burner will heat the oil and water and 55 initiate the thermo-siphonic flow of water through the passage. After they have been heated sufficiently, the Bunsen burner may be extinguished.

The heat developed by the burner will act 60 on the water passage 15 and oil passage 13, and tend to raise the temperature thereof, but since the water passage is nearer the furnace than the oil passage, it will experience greater heat than the oil passage. The temperature of the oil will rise up to a prede-

termined point, such, for example, as 160° F., and the thermostat may be so adjusted that when the oil attains a temperature above this point, it will automatically open the valve 37 and allow the cooling water to 70 flow through the passage 15. Since the latter is closely adjacent to the oil passage, the oil will be cooled thereby. This cooling effect will continue until the temperature thereof lowers to the predetermined point, 75 and thereupon, the thermostat will return the valve to its seat and cut off the flow of cooling water through the passage 15. Thus, by the means described, the oil flowing through the passage 13 will be automatically 80 maintained at the desired temperature for efficient combustion effect.

Any suitable form of burner may be provided in connection with the temperature controlling device for the oil described. In 85 the present instance of the invention, a burner is provided of substantially the same construction as disclosed in my copending application Serial No. 219,958, filed March 2, 1918.

This burner comprises a casing or nozzle 63 formed to fit within the housing cylinder 3, and preferably spaced somewhat therefrom. Mounted in said casing is an oil conducting tube 65 substantially smaller 95 than the casing 63 so as to leave an annular passage 67 between them for delivery of compressed air or other atomizing agent, as more fully hereinafter described.

Mounted on ball bearings carried by the 100 tube 65 is a shell 69 provided with a flaring nozzle 71. A turbine 73 is mounted on the shell 69 in the path of the fluid forced through the annular passage 67 and rotated thereby. The construction is such that the 105 oil delivered from the tube 65 to the nozzle 71 will be whirled outward by the latter under the influence of centrifugal force into the path of the annular stream of fluid issuing from the nozzle 63. Thus, the oil will 110 be atomized or broken up by the fluid into substantially a gaseous state for efficient combustion effect.

Suitable means may be provided to conduct oil from the passage 13 referred to, in 115 the housing jacket, to the tube 65. In the present instance, this means comprises an elbow tube 75 having one end connected to the rear end of the casing 63 and communicating with the tube 65. This elbow tube 120 has a portion 77 projecting substantially parallel to the axis of the burner, and threaded in a lateral extension 79 projecting from the casing 63.

Mounted in the tube portion 77 and telescoping therewith is a tube 81 having an end threaded into the tapped hole 19 referred to, on the housing. A stuffing box 83 may be provided between the tube portion 77 and tube 81 to prevent leakage therebetween. 130

The end 85 of the tube 81 may be closed, and a port 87 may be provided in the side of said tube for communication with a port 89 in the elbow tube leading to the tube 65.

5 The construction is such that the burner may be moved relatively to the housing to and from active firing position. In the course of this movement, the tube portion 77 will slide along the tube 81. When the 10 burner is moved to firing position, the port 87 will communicate with the port 89 and admit oil to the burner, and when the latter is retracted from firing position, the port 87 will be moved out of registration with the 15 port 89 and cut off the supply of oil to the burner.

It is desirable that any residual oil in the burner passages shall be withdrawn therefrom when the burner is shut down, in order 20 to prevent carbonization of such residual oil on passages of the burner and clogging the same. Residual oil in the burner passages is desirably withdrawn therefrom on movement of the burner from firing position by the pump-like or suction effect of the tube 81 in the tube portion 77.

The burner is guided partly in its movements to and from firing position by the tube 81. To further contribute to the guidance and support of the burner, a rod 91 may have an end connected to the support and project rearward therefrom substantially parallel to the tube 81. This rod may project through a lateral extension 95 on the burner, and the rearward movement of the latter may be limited by a cotter pin 95 in said rod.

Compressed air or other suitable atomizing agent may be conducted to the burner 40 from a suitable source of supply through a neck 97 on the support, and adapted to communicate with a neck 99 projecting laterally from the burner casing 63 and communicating with the annular passage 65 therein. A 45 butterfly valve 101 may be mounted in the neck 97 on a rock shaft 103 having an arm 105 fast thereon connected by a link 107 with a screw pin 109 on the neck 99. The construction is such that when the burner 50 is moved to firing position, the valve will be automatically rocked by the connections described to admit atomizing fluid into the burner, and when the burner is moved from firing position, the valve will be rocked by 55 the connections described to cut off the supply of atomizing fluid from the burner.

In operation, the oil coming from its source of supply will pass through the jacket passage 13 and be heated thereby, as described, to the temperature desired. It will 60 flow thence through the tube 81, and the elbow tube 75 to the tube 65 within the burner, and will flow therefrom through the nozzle 71 and be delivered thereby. The 65 compressed air or other atomizing fluid will

flow from its source of supply through the necks 97 and 99 into the annular passage 67, and upon flow through the latter will engage the turbine 73 and impart rotation thereof and to the nozzle 71. The compressed air or fluid will flow thence in an annular stream through the nozzle 63 and be delivered therefrom with atomizing effect on oil whirling outwardly from the nozzle 71. 70

75 It will be understood that the invention is not limited to the specific embodiment shown, and that various deviations may be made therefrom without departing from the spirit and scope of the appended claims. 80

What is claimed is:

1. The combination of a burner having a water jacket adapted to be heated by heat developed by the burner, thermo-siphonic means for supplying water to said jacket, 85 means to conduct oil adjacent to said water jacket preliminarily to delivery of the oil to the burner, that the oil may be subjected to heating or cooling influence from the water in said jacket, a valve for the water supply means, and a thermostat responsive to the temperature of the water automatically to control said valve. 90

2. The combination of a burner for fuel oil, a receptacle disposed to be heated by the heat developed by the burner and provided with oil and water containing conduits, means for delivering oil to the receptacle to heat the oil preliminary to combustion thereof, and temperature controlled 95 means for regulating the flow of water through its conduit to thereby control the temperature to which the oil is heated. 100

3. The combination of a burner, a burner housing disposed to be subjected to heat developed by the burner, means for conducting oil through the housing and subjecting it to the heat of the housing, means for conducting water through the housing to regulate the heat of the oil, and means automatically to control the supply of water through the housing to maintain the oil at a predetermined temperature for delivery to the burner. 110

4. The combination of a burner for fuel 115 oil, means to supply oil thereto, means heated by the heat developed by the burner for automatically heating the oil preliminarily to combustion, means for automatically controlling the temperature to which the oil 120 is heated, and an auxiliary heater for heating the fuel oil prior to the development of heat by the burner.

5. The combination of a burner housing adapted to be subjected to heat developed by 125 the burner and having adjacent oil and water jacket passages, means to supply water to said water passage that the water may be heated by said heat and transmit heat to the oil in the adjacent oil passage 130

- in preparation for combustion, and thermostatic means for regulating the flow of water in said water passage, thereby automatically to maintain the oil in the oil passage at a predetermined temperature. 55
6. The combination of a burner, a receptacle having a water passage adapted to be subjected to heat developed by the burner, means to supply oil to the burner including a passage adjacent to the water passage, that the temperature of the oil in the oil passage may be controlled by the temperature of the water in the water passage, and means automatically to supply cooling water to the water passage as required to maintain the oil in the oil passage substantially at a predetermined temperature preliminarily to combustion of the oil. 65
7. The combination of a burner for fuel oil, oil and water containing chambers surrounding the burner and disposed to be subjected to heat developed by the burner, means to circulate water through the water chamber to regulate the temperature of the oil, and temperature responsive means for regulating the flow of water through the water chamber. 70
8. The combination of a burner for fuel oil, means to supply oil thereto, and thermostatic siphonic means for supplying water adjacent to the oil supply means, thereby automatically to control the temperature of the oil preliminarily to combustion thereof. 75
9. The combination of a burner housing having oil and water passages adapted to be subjected to heat developed by the burner, a burner mounted in said housing and receiving oil from said oil passage, thermo-siphonic means for supplying cooling water to said water passage to regulate the temperature of the oil in the oil passage, and a thermostat means for controlling the supply of water from said thermo-siphonic means to said water passage. 80
10. The combination of a burner housing, a burner mounted thereon movable relatively thereto to and from firing position, said housing having oil and water passages therein in adjacent relation that the temperature of the oil in the oil passage may be regulated by the temperature of the water in the water passage, means to conduct oil from the oil passage to the burner when the latter is in firing position, and temperature responsive means automatically to supply water to said water passage. 85
11. The combination of a burner housing, a burner mounted therein, said housing having water and oil conducting passages adapted to be subjected to heat developed by the burner, means to conduct oil from the housing to the burner including telescoping tubes, and a thermostat controlled means for regulating the flow of water through the water passage in the housing. 90
12. The combination of a burner housing having oil and water conducting passages therein adapted to be subjected to heat developed by the burner, a stand pipe, a branch pipe leading from said stand pipe to the water passage, a branch pipe leading from said water passage to said stand pipe, a valve for controlling the flow of water through said water passage, and a thermostat responsive to temperature changes in the water for automatically opening and closing said valve to regulate the cooling effect of the water in the water passage on the oil in the oil passage. 95
13. The combination of a burner housing having adjacent oil and water conducting passages therein, and having the water passage disposed between the oil passage and the heat developed by the burner and in position to be heated by the burner, means to supply water to said water passage, a valve for regulating the flow of water through said water passage, and a thermostat for operating said valve having provision for varying the normal position of said valve. 100
14. The combination of a housing having oil and water conducting passages therein, a casing communicating with said water passage, a valve and its seat mounted in said casing, and a thermostat exposed to the water and operable to control said valve in response to variations in the temperature of the water in said passage. 105
- In testimony whereof, I have signed my name to this specification.

MILTON A. FESLER.
